(57) **CLAIM**

The ornamental design for an extended drive ceiling fan, as shown and described.

DESCRIPTION

FIG. 1 is a bottom perspective view of an extended drive ceiling fan, showing the new design;

FIG. 2 is an elevation view with the opposite elevation being a mirror image;

FIG. 3 is an end view with the opposite end being a mirror image;

FIG. 4 is a bottom view; and,

FIG. 5 is a top view.

The broken line showings of FIGS. 1–5 are for the purpose of illustrating unclaimed portions of the extended drive ceiling fan and form no part of the claimed design.
